UNITED STATES PATENT OFFICE.

FRANK A. LYONS, OF CHARLOTTE, NORTH CAROLINA.

TROUSERS-STRETCHER.

1,153,128.

Specification of Letters Patent.

Patented Sept. 7, 1915.

Application filed February 7, 1914, Serial No. 817,226. Renewed February 6, 1915. Serial No. 6,638.

To all whom it may concern:

Be it known that I, FRANK A. LYONS, a citizen of the United States, residing at Charlotte, in the county of Mecklenburg and

5 State of North Carolina, have invented new and useful Improvements in Trousers-Stretchers, of which the following is a specification.

The invention relates to trousers 10 stretchers, and has for its primary object to provide a stretcher wherein the trousers can be held in shape so as to prevent the wrinkling thereof and sustain the same creased to give a fresh and neat appearance 15 thereto when worn.

Another object of the invention is the provision of a trousers stretcher wherein the same is made in the form of a compressible frame which can be readily placed within 20 the trousers to hold the leg portions taut and against wrinkling, the frame being of novel form to prevent the collapsing thereof while in use.

A further object of the invention is the 25 provision of a trousers stretcher which is simple in construction, strong, durable, reliable and efficient in operation, and inexpensive in manufacture.

With these and other objects in view, the 30 invention consists in the construction, combination and arrangement of parts as will be hereinafter fully described, illustrated in the accompanying drawing, and pointed out in the claim hereunto appended.

35 In the drawing, Figure 1 is a side elevation of a trousers stretcher constructed in accordance with the invention. Fig. 2 is a similar view, looking toward the opposite side thereof. Fig. 3 is a side elevation of 40 one of the stretchers of the frame. Fig. 4 is a sectional view on the line 4—4 of Fig. 1.

Similar reference characters indicate corresponding parts throughout the several views in the drawing.

45 Referring to the drawing in detail, the trousers stretcher comprises a pair of compressible frames, only one of which is illustrated, and includes side members 5, preferably made from relatively stiff wire, arranged 50 in convergent relation to each other, and are of the same length with respect to each other. The side members 5 are formed

with inwardly converging limbs 6 and 7 respectively, having out-turned terminals 8 which are clamped together in a manner 55 presently described.

The limbs 6 and 7 are formed with single coils 9 to which are connected cross links 10, the same being formed with eyes 11 which engage the coils 9, and these links serve to 60 prevent the separation of the ends of the limbs when clamped together, and also obviate the possibility of side swinging movement of the side members 5 when the frame is compressed for the placing of the same in 65 the leg portions of the trousers.

One pair of the terminals 8 is formed with eyes 12 which embrace the limbs 6, and surrounding this pair of terminals 8 is the sleeve portion 13 of a clamping plate 14, 70 the same being also formed with a sleeve portion 15 which embraces the link 10 connected to the coils 9 formed in the limbs 6, while embracing the other pair of terminals 8 on the limbs 7 is a sleeve 16, the same being formed with a wing or ear 17 bent to provide a sleeve 18 which embraces the other link 10 connected to the coils 9 bent from the limb 7 so that it will be apparent that the link 10 will be held against displacement 80 75 and also the ends or terminals 8 of the limbs 6 and 7 will be securely joined together.

In the use of the trousers stretcher the pair of compressible frames are inserted in the trousers so as to extend within the leg 85 portions thereof, it being understood of course that the frames are compressed so that they may be readily inserted in the said leg portions, and when the frames are released they will stretch the trousers taut to 90 prevent the wrinkling thereof and to assure the creasing of the leg portions.

From the foregoing it is thought that the construction and manner of use of the invention will be clearly understood, and 95 therefore a more extended explanation has been omitted.

What is claimed is:—

A trousers stretcher comprising a pair of resilient wires each bent into loop form, 100 the end portions of each loop being bent to form single coils, an eye formed on one terminal of each loop, clamping plates embracing the end terminals of the loops,

stretches of the said loops being trained through the eye terminals, links engaged with the coils for preventing the separation of the terminals of the loops from the clamping plates, and means on the plates for engaging the links.

In testimony whereof I affix my signature in presence of two witnesses.

FRANK A. LYONS.
